(57) **CLAIM**

I claim the ornamental design for a removable toilet bucket, as shown and described.

DESCRIPTION

FIG. 1 illustrates a front right perspective view of the present invention.

FIG. 2 illustrates a back left perspective view of the present invention.

FIG. 3 illustrates a front view of the present invention.

FIG. 4 illustrates a back view of the present invention.

FIG. 5 illustrates a left side view of the present invention.

FIG. 6 illustrates a right side view of the present invention.

FIG. 7 illustrates a top side view of the present invention; and,

FIG. 8 illustrates a bottom side view of the present invention.
